UNITED STATES PATENT OFFICE.

WILLIAM H. GIBSON, ALLAN M. GIBSON, AND GEORGE S. KLUTTZ, OF CONCORD, NORTH CAROLINA.

BOLL-WEEVIL EXTERMINATOR.

Application filed July 12, 1922. Serial No. 574,531.

To all whom it may concern:

Be it known that we, WILLIAM H. GIBSON, ALLAN M. GIBSON, and GEORGE S. KLUTTZ, citizens of the United States, residing at 5 Concord, in the county of Cabarrus and State of North Carolina, have invented new and useful Improvements in Boll-Weevil Exterminators, of which the following is a specification.

10 This invention relates to insect destroyers and has for its object the provision of a novel machine adapted to be drawn along the ground for removing weevils from growing cotton plants and for gathering up 15 dead or live weevils which may be on the ground and also all the punctured squares, the device operating by suction.

An important object is the provision of a 20 device of this character in which the hoods or nozzles are carried by flexible members which will permit effective use regardless of the distance between the rows or hills.

Still another object is the provision of an 25 insect destroyer of this character in which the hood elements are provided not only with novel cut-off means but with adjustable stops by means of which the position of the hoods above the ground may be regulated depending upon the height of the 30 growing plants.

A further object is the provision of interchangeable hoods of different types and also nozzles, the latter being efficiently designed 35 to exert a sweeping action for gathering up punctured squares.

An additional object is the provision of a device of this character which will be simple and inexpensive in manufacture, easy to operate and control, efficient and durable in 40 service and a general improvement in the art.

With the above and other objects and advantages in view the invention consists in the 45 details of construction to be hereinafter more fully described and claimed and illustrated in the accompanying drawings in which:

Figure 1 is a side elevation of the device showing one form thereof,

50 Figure 2 is a plan view,

Figure 3 is a rear elevation showing the use of one form of hood and showing various height adjustments,

Figure 4 is a longitudinal section through one of the suction control elements and hood 55 associated therewith,

Figure 5 is a longitudinal section through a modified form of hood,

Figure 6 is a side elevation of still another type of hood,

Figure 7 is a rear elevation thereof.

Referring more particularly to the drawings the numeral 15 designates a supporting frame which may be constructed of suitable wooden bars or of angle iron of any desired weight and cross sectional shape and which is here shown as being rectangular and provided at its front end with converging bars 16 carrying hounds 17. An axle 18 is secured to or forms a part of this frame and 70 carries a pair of ground engaging wheels 19.

As the device is intended to be drawn by one horse I provide thills 20 carrying a fifth wheel 21 movably mounted upon the hounds 17 in the ordinary manner. Depending 75 from this fifth wheel structure is a yoke 22 carrying a single ground engaging wheel 23.

The frame 15 preferably has a platform 24 secured thereon and upon which is mounted a seat 25 for the operator. This platform 80 provides ample space upon which may be mounted tool boxes or any receptacle which may be needed for the carrying of any articles or auxiliary apparatus such as tools and the like which may be needed during the 85 operation of the machine.

Mounted upon the platform is a power device 26 such as a small gas engine and which operates a rotary blower 27 mounted within a casing 28 and discharging into a gathering 90 receptacle 29 in the same manner as a vacuum type power driven sweeper. The inlet pipe 30, to the casing 28 is formed with two oppositely extending horizontally disposed branches 31 from which lead relatively small 95 connections 32. The above described parts are all common to both forms of the invention. The pipe 26^a is an air pipe provided simply for cooling the motor by means of the fan in the blower and might be omitted if the engine were equipped with an independent fan.

In Figures 1 to 3 I have shown some of the connections 32 as closed off by any suitable means and consequently rendered inactive 105 while the remaining ones, six in number are

shown as having flexible hoses 33 connected therewith so that six rows of plants may be treated at one time. Each hose carries a control member shown in detail in Figure 4 and consisting of a cylinder 34 having a lateral connection 35 for the hose and having its upper end closed and formed with a handle 36 and its lower end open and provided with a valve seat 37. Slidable through the closed end is a stem 38 which has its upper end carrying a handle 39 above the handle 36 and normally pressed upwardly by a spring 40. Carried by the lower end of the stem is a valve 41 in the nature of a disk adapted to close upon the seat 37.

The connecting members may carry selected ones of a series of hoods which are shown in detail in Figures 4 to 7. The type shown in Figure 4 consists of a cylindrical shell 42 open at its bottom and having its upper end formed with a frusto-conical portion 43 mounted upon the cylinder 34 and held thereon by any desired means, the means being however of such a nature as to permit removal of the hood when such is desired. Carried by the shell 42 is a vertically adjustable slidably mounted foot member 44 designed to engage the ground for regulating the height of the hood with respect thereto.

In the operation, the device is drawn along the ground and the hoods 42 are disposed over the rows of growing plants so that when the suction device is operated the suction produced through the hoods will operate to suck in the insects upon the growing plants and discharge them into the gathering receptacle 29 in which they may subsequently be destroyed by any preferred means. The adjustable foot members 44 govern the position of the hoods in accordance with the height of the growing plants, various adjusted positions being shown in Figure 3. It is intended that an operator be provided for each nozzle in this form of the device which is used when the plants are very young.

In Figure 5 we have shown a modified form of hood which includes merely a frusto-conical shell 45. This form is designed particularly for use when the plants have reached a size too great to permit the hoods 42 to be used, this form being moreover designed particularly for use when the cotton plants are in hills instead of rows.

In Figures 6 and 7 we have shown still another type of hood which is particularly advantageous when used in the treatment of plants growing in rows and chopped out in such a way that they are comparatively close together. This hood is designed by the numeral 46 and is of shell like formation but U-shaped in end view so as to straddle the plants, the forward end being flaring as shown at 47 so as to exert a brushing action upon the plants passed over.

From the foregoing description and a

study of the drawings it will be apparent that we have thus provided a simply constructed and easily operated and controlled machine which will efficiently exterminate boll weevils, or at least reduce their existence to such an extent that their destructive work will be almost eliminated, the device having the notable advantage of removing the insects not only from the plants but also from the ground and additionally picking up all the squares and other débris which have fallen. It is also to be noted that we have provided ample means for rendering any of the nozzles inactive at will, the plunger controlled valves operating efficiently for carrying out this purpose. Owing to the simplicity of the construction of the entire device and the fewness of the parts, it is apparent that there is very little to get out of order so that the device should have a long life and satisfactorily perform all the functions for which it is intended.

While we have shown and described the preferred embodiment of the invention it is of course to be understood that we reserve the right to make such changes in the form, construction and arrangement of parts as will not depart from the spirit of the invention or the scope of the subjoined claims.

We claim:

1. A boll weevil exterminator comprising a wheel supported frame, a power driven suction device on the frame, and a plurality of hoses connected with the suction device and carrying nozzles, and means for establishing or cutting off communication through any number of said nozzles, said means consisting of a cylinder interposed between the hose and the suction pipe and provided with a valve seat, a handle at the top of the cylinder, a stem slidable through said handle and carrying a valve co-operating with said seat, and an upwardly spring pressed handle on said stem above said first named handle.

2. A device of the character described comprising a wheel supported frame provided with draft means, a power device on the frame, a suction blower driven by said power device and mounted on the frame, said blower having a branched inlet pipe carrying a plurality of selectively closable connections, flexible conduits connected with said connections, manually controllable valve members carried by said hoses for establishing or cutting off communication therethrough, hoods carried by said control members, and vertically adjustable foot members carried by the hoods and engageable with the ground for varying the position of the hoods with respect thereto.

3. In a vacuum type insect exterminator, a nozzle consisting of a cylindrical shell having its lower end carrying a flaring hood, a valve located within the cylinder at

its juncture with the hood and having an operating stem extending axially through and beyond the upper end of the cylinder.

4. In a vacuum type insect exterminator, a nozzle consisting of a cylindrical shell having its lower end carrying a flaring hood, a valve located within the cylinder at its juncture with the hood and having an operating stem extending axially through and beyond the upper end of the cylinder, and a foot member vertically slidably adjustably mounted upon the hood and engageable with the ground whereby to space the hood away from the ground.

5. In a vacuum type insect exterminator, a nozzle consisting of a cylindrical shell having its lower end carrying a flaring hood, a valve located within the cylinder at its juncture with the hood and having an operating stem extending axially through and beyond the upper end of the cylinder, the hood being of arch shape whereby to straddle a row of plants.

In testimony whereof we affix our signatures.

WILLIAM H. GIBSON.

ALLAN M. GIBSON.

GEORGE S. KLUTTZ.
